FIG. 1 is a side elevation of a self rewinding reel unit for rope, the broken line showing of a mounting surface being for illustrative purposes only.

FIG. 2 is a rear end view.

FIG. 3 is a top plan view.

FIG. 4 is a view taken substantially on line 4—4 of FIG. 1, and shows the sectional configuration, on such line, of the case of the unit.

FIG. 5 is a front end elevation of the unit mounted as in FIG. 1.

FIG. 6 is a side elevation of the unit as seen from the opposite side of FIG. 1.

In the views where it appears, the rope is shown foreshortened or broken away.

I claim:

The ornamental design for a self-rewinding reel unit for rope, as shown and described.
